UNITED STATES PATENT OFFICE.

HENRY M. RUDEN, OF WEST HAVEN, CONNECTICUT.

EXERCISING APPARATUS.

1,258,469.

Specification of Letters Patent.

Patented Mar. 5, 1918.

Application filed September 26, 1917. Serial No. 193,275.

To all whom it may concern:

Be it known that I, HENRY M. RUDEN, a citizen of the United States, residing at West Haven, in the county of New Haven and State of Connecticut, have invented a new and useful Improvement in Exercising Apparatus; and I do hereby declare the following, when taken in connection with the accompanying drawings and the characters of reference marked thereon, to be a full, clear, and exact description of the same, and which said drawings constitute part of this application, and represent in—

Figure 1 a view in front elevation of one form which my improved exercising apparatus may assume.

Fig. 2 a view thereof in side elevation.

Fig. 3 a plan view thereof showing a rowing-seat combined therewith.

Fig. 4 a detached view in elevation of one of the weight-frames.

My invention relates to an improved exercising apparatus for use in gymnasiums and in private homes, the object being to produce a simple, compact and durable apparatus designed and constructed to compel the exerciser to make predetermined co-extensive circular movements with his arms, whereby a symmetrical development of his body is promoted.

With these ends in view, my invention consists in an exercising apparatus having two handles or grips turning upon centers and connected with weights, the said handles or grips imposing predetermined, co-extensive circular movements upon the arms of the exerciser.

My invention further consists in certain details of construction, and combinations of parts as will be hereinafter described and pointed out in the claims.

In carrying out my invention as herein shown, I employ two exercising wheels 2 and 3 located in the same horizontal plane, each provided on its rim with an upstanding grip or handle 4, and designed to be spaced apart so that the outer edges of their rims will be separated by about the limit of the reach of the exerciser when his arms are fully extended. The wheel 2 is secured by a stud 5 to the upper end of an upright 6 having a foot 7 by means of which it is fastened to the floor, while the wheel 3 is pivoted by a corresponding stud 8 upon the upper end of an upright 9 provided with a foot 10 by means

of which it is secured to the floor. These uprights will be about waist high.

The upright 6 is provided with two branch-fittings 11 from which two parallel pipes 12 extend into corresponding but larger pipes 13 carried by branch-fittings 14 upon the upright 9. By telescoping the pipes 12 with respect to the pipes 13, the uprights 6 and 9 may be moved toward or away from each other, according to the size and arm-reach of the exerciser. When the uprights have been placed in proper position as required, their feet 7 and 10 are fastened to the floor.

The handles 4 are mounted upon studs 15 upstanding from the rims of the wheels 2 and 3, the studs being furnished at their lower ends with loops 16 to which are attached weight-cords 17 running rearward to vertically movable weight-holders 18 each provided with a stack of weights 19 and each formed at its lower end with a plate 20 having projecting lugs 21 perforated for the reception of parallel guide-rods 22 having their upper and lower ends secured in rectangular weight-frames respectively located directly back of the uprights 6 and 9 aforesaid. Each of the said weight-frames 23 is mounted upon a short standard 24 terminating in a foot 25 adapted to be fastened to the floor and corresponding to the feet 7 and 10 aforesaid. The weight-cords 17 pass over sheaves 26 the frames 27 of which are pivotally mounted in clips 28 secured to the upper cross pieces of the weight-frames 23. The weight-cords 17 pass downward from the sheaves 26, over pulleys 29 in the upper ends of the weight-holders 18, the extreme ends of the weight-cords being extended upward and fastened to the clips 28. The respective weight-frames 23 are rigidly connected with the uprights 6 and 9 by means of stretcher members 30. It will be understood that in adjusting the apparatus in width to the reach of the exerciser, either the left hand upright 6 and its connected weight-frame must be moved toward or away from the right hand upright 9 and its weight-frame, or vice versa, the frame of the apparatus, as thus constructed, consisting of two separately organized parts telescoped together.

In using my improved apparatus, it will preferably be adjusted so that when the wheels are turned to bring the handles into

their outermost positions, the exerciser is just able to reach them with his arm fully outstretched. In exercising, the exerciser takes a central position in front of the machine between the two wheels, and turns them simultaneously or alternately, toward him or away from him according to the muscles which it is desired that his exercises shall bring into play. In any event, 10 the wheels which are on the same level and which are of the same diameter, will serve to guide his hands and arms, and impose not only circular movement upon them, but what is more important, an equal sweep of 15 movement for each arm. The muscles on the respective sides of the body, thus brought into play, are therefore contracted and relaxed identically, tending toward their equal development, whereas in an exercising apparatus of the pulley-weight type wherein 20 the arms are neither guided nor equalized in their movement, the development of the muscles tends to be unequal and lop-sided. In using my improved apparatus, moreover, 25 the turning of the wheels is found to be less fatiguing than the reciprocating movement called for by pulley-weights, so that the exerciser is carried along, as it were, and does his exercises with the minimum of 30 fatigue.

In the apparatus shown in Figs. 1 and 2, the exerciser is designed to stand upright in front of it, midway of its wheels, but the principle on which my apparatus is 35 constructed is equally applicable for use in bringing into play and symmetrically developing other muscles than those brought into play by the apparatus shown in the said figures.

40 In Fig. 3 I have shown my apparatus combined with a sliding rowing-seat 31 on tracks 32 supporting at their forward ends, the usual foot-rests 33 with their straps 34. In the use of this combined apparatus, the 45 exerciser works himself back and forth on the sliding seat 31, while he simulates the movement of rowing by turning the wheels 2 and 3. It is also too apparent to require 50 illustration, that, if desired, the wheels 2 and 3 might be arranged in a horizontal plane above the head of the exerciser with their handles depending rather than standing. In such an arrangement, the 55 exerciser would reach upward with his arms and rotate the wheels in the manner already

described. While I have herein shown the use of wheels, which is my preference, it is apparent that the guiding and impositional effect will be the same if they are replaced by crank-arms provided with handles and connected by pulley cords with weights.

I claim:—

1. In an exercising apparatus, the combination with a two-part frame the respective parts of which are adjustable toward and away from each other, of two handle-grips respectively mounted upon the two parts of the frame for being operated by the arms of an exerciser stationed between them, 65 and weights connected with the respective handle-grips which impose predetermined co-extensive circular movements upon the arms of the exerciser.

2. In an exercising apparatus, the combination with two wheels located in the same horizontal plane, provided with handle-grips and relatively positioned to be operated by the respective arms of the exerciser; of weights connected with the respective wheels which impose predetermined, co-extensive circular movements upon the arms of the exerciser.

3. In an exercising apparatus, the combination with a two-part frame the respective parts of which are adjustable toward and away from each other, of wheels mounted in the same plane upon the respective parts of the frame and each provided with a handle-grip, and weights connected with the respective wheels.

4. In an exercising apparatus, the combination with a two-part frame the parts of which are adjustable toward and away from each other and each part of which comprises 95 an upright at its front end and a weight-frame at its rear end; of wheels mounted in the same plane upon the upper ends of the said front uprights, weight-holders located within the said weight-frames, 100 and weight-cords connecting the respective wheels and weight-holders.

In testimony whereof, I have signed this specification in the presence of two subscribing witnesses.

HENRY M. RUDEN.
